CLAIM

The ornamental design for a wheel, as shown and described.

DESCRIPTION

FIG. 1 is a front view of a wheel showing our new design; FIG. 2 is a right perspective view thereof; and, FIG. 3 is a left perspective view thereof.

It will be understood that the broken lines shown in the drawings illustrate portions of the wheel that form no part of the claimed design.

1 Claim, 3 Drawing Sheets

FIG. 1

FIG. 2

FIG. 3
